[57]

ABSTRACT

A pressurized dispensing package of the type which includes an upstanding material dispensing stem having an actuator assembly mounted thereon which includes an annular resilient sealing member including a movable valving member, the valving member includes a frusto-conical actuating surface and a refill passage, a portion of which extends angularly of the direction of movement of the valving member to a port in the actuating surface. The sealing member is flexibly movable in response to movement of the valving member between a first position in which the dispensing passage is open and the sealing member seals the refill passage from the stem and a second position in which the refill passage is open and the sealing member seals the assembly dispensing passage from the stem.

FIG 1

FIG 2

FIG 3

FIG 4

PRESSURIZED DISPENSING PACKAGE

SUMMARY OF INVENTION

This invention relates to pressurized dispensing packages and more particularly to systems that permit the refilling of such pressurized dispensing packages.

Pressurized containers are used for dispensing a wide variety of products including insecticides, deodorants, antiperspirants, shaving preparations, dessert toppings, etc. Conventional pressurized dispensing packages are filled by the manufacturer and are discarded by the consumer after those contents have been dispensed. A relatively large size pressurized dispensing package reduces the cost to the user but such large containers are cumbersome and inconvenient and small size pressurized dispensing packages, while convenient to store and use, are relatively expensive in terms of material dispensed. It has been proposed that the use of pressurized dispensing packages of relatively small size might be extended by arrangements that permit the user to easily and safely refill one relatively small container refilled from a larger sized pressurized dispensing package, thus providing the consumer with greater convenience and reducing his overall cost. Such a system, in addition to making more economical the use of small pressurized dispensing packages, would also increase the flexibility and convenience with which various products packaged in this manner can be used.

It is an object of this invention to provide novel and improved systems permitting the transfer of material from a pressurized dispensing package to a smaller dispensing package which a consumer can easily and safely operate. Such systems, in addition to making economical the purchase of small devices for special use, would also reduce the overall cost to the consumer of the dispensed product, and increase the flexibility and convenience with which various dispensed products can be used.

Another object of the present invention is to provide novel and improved refill systems in which one of the devices includes a simple and inexpensive actuator assembly which is biased towards a normal dispensing configuration and which may be displaced by interaction with a cooperating device into a refilling configuration in which the one device is refilled from the cooperating device. Other objects include providing in such systems the structure required to prevent accidental discharge through the wrong one of the device's refilling and dispensing passages.

In accordance with the invention there is provided a pressurized dispensing package including a container for storing material to be dispensed under pressure, a discharge passage structure and a valve assembly for controlling the discharge of the material from the container through the discharge passage structure, and an actuator device mounted on the discharge passage structure. The actuator device includes a dispensing passage having an inlet port at one end and a dispensing port at the other end and a transfer passage providing communication between the discharge passage structure and the inlet port of the dispensing passage, a resilient sealing member mounted adjacent the inlet port; and a valving member mounted in engagement with the sealing member for movement relative to the transfer passage defining structure. The valving member defines a refilling conduit extending through

the valving member to a port at an exterior surface thereof, and the sealing member is movable in response to movement of the valving member between a first position in which the sealing member seals the refilling conduit from the transfer passage and a second position in which the sealing member seals the inlet port of the dispensing passage and the refilling conduit is in communication with the transfer passage.

In a preferred embodiment, the sealing member is 10 annular in configuration and the valving member includes a frusto-conical transition portion and an end portion disposed in the central opening of the sealing member. A spring biases the valving member towards the first position in which a flange on the valving member engages a wall in the chamber in which the valving member is disposed and a portion of the valving member that extends above the flange projects through an opening in the wall of the chamber. The refilling 15 passage terminates in a port at the surface of this extending portion and a recess is provided surrounding the port of the refilling passage which cooperates with a mating surface of a second cooperating package for refilling the first package from the second cooperating 20 package.

The invention provides a convenient, reliable and economical system enabling a user to refill a small (daughter) pressurized dispensing package from a larger (mother) dispensing package. The daughter package may be of the size suitable for carrying in a purse, for example, and need not be discarded when the material initially loaded into it has been dispensed. Rather, the daughter package may be readily refilled 25 from the mother package.

Other objects, features and advantages will appear from the following detailed description of a preferred embodiment of the invention, taken together with the attached drawings, in which:

FIG. 1 is a perspective view of a pressurized dispensing package embodying the present invention;

FIG. 2 is a cross-sectional view of the actuator assembly of the package of FIG. 1 in its dispensing configuration;

FIG. 3 is a cross-sectional view of the actuator assembly of a cooperating package in its dispensing configuration; and

FIG. 4 is a cross-sectional view of the actuator assemblies of FIGS. 2 and 3 in engagement and in their 50 respective refilling configurations.

DESCRIPTION OF PARTICULAR EMBODIMENT

Referring now to FIGS. 1 and 2, there is shown a pressurized dispensing package, generally designated 55 10, including a can body 12 having a top opening on which is mounted a cup 14. A valve having discharge passage structure in the form of upstanding valve stem 16 is supported in the central bore of cup 14.

An actuator assembly, generally designated 17 and 60 including a main body 18, is mounted on stem 16. The upper portion of the stem is tightly fitted within a socket 20 (FIG. 2) at the support base. An internal transfer passage 22 extends upwardly from socket 20 to substantially midway the height of body 18, the upper portion 30 of passage 22 is frusto-conical in configuration. A dispensing passage 24 extends, generally perpendicular to the axis of stem 16, from an inlet port at

the upper end of portion 30 of passage 22 to dispensing port 25 in conical nozzle opening 26.

As shown, a cylindrical chamber 32, of diameter greater than that of discharge passage 22, extends downwardly from the top of body 18 to passage portion 30 and terminates in an annular surface 34 perpendicular to the actuator axis and coplanar with the top of passage 24. The chamber 32 is closed at its top by a cap 36 having central opening 38 and an annular depending rim 39 engaging body 18. A circular flexible, resilient sealing gasket or washer 40 of soft rubber or similar material, having a central opening 42, is seated on surface 34.

A valving member 44, circular in cross-section, is mounted coaxially within chamber 32. The lower end of member 44, adjacent gasket 40, includes a frusto-conical transition portion 46 and a cylindrical tip 48. Tip 48, as shown in FIG. 2, is seated within the seals gasket opening 42. Valving member 44 includes an annular stop flange 50 spaced from tip 48 that engages the underside of cap 36. Helical spring 52, of substantially less strength than the spring within the dispensing valve, surrounds member 44, one end of the spring engaging flange 50 and the other end of the spring engaging the top of gasket 40.

The upper portion 54 of valving member 44, above flange 50, extends through opening 38 of cap 36. A cylindrical recess 56 is provided in the end of upper portion 54. A refill passage 58 of smaller diameter than recess 56 extends axially of the valving member from recess 56 to a point within transition portion 46 and thence angularly to port 59 in the frusto-conical surface of portion 46. A cover 60, having a socket 62 for receiving the projecting upper portion 54 of valving member 44, is secured to cap 36 by integral hinge 64.

As shown, helical spring 52 biases the valving member of assembly 17 toward a normal dispensing configuration (FIG. 2) in which material dispensed through valve stem 16 will flow through the assembly to port 25 along the path defined by passages 22 and 24. The resilience of gasket 40 and spring 52 press flange 50 of the valving member against the underside of cap 36, tip 48 sealing the center opening of gasket 40, and gasket 40 being flat (i.e., unflexed) across the upper end of passage 22. Also, for normal dispensing, cover 60 is closed (see FIG. 2) with upper portion 54 of the valving member 44 within cap socket 62. If the valve of container 10 is opened, typically by pressing downwardly on the top 61 of cover 60, material will flow from container 10 along the path described above and out port 25.

Referring now to FIG. 3, there is shown an actuator assembly 17' fitted on the valve stem 16' of a refill aerosol device 10'. Except for those differences required to provide interactuator sealing between assemblies 17 and 17', assembly 17' is substantially identical to assembly 17. As shown, the height (above flange 50') of upper portion 54' of the valving member 44' of assembly 17' is slightly less than the thickness of cap 36' (and also slightly less than the depth of recess 56) so that, when flange 50' engages the underside of the cap 36', no portion of valving member 44' extends above the cap 36'. Accordingly, assembly 17' does not require a cover corresponding to cover 60 to prevent accidental actuation of valving member 44'. Further,

the diameter of upper portion 54' of valving member 44' is slightly less than the diameter of recess 56 of member 44, and valving member 44' does not include a recess corresponding to recess 56. Central opening 38' of assembly 17' and opening 38 of assembly 17 have substantially the same diameter, there being an annular gap between upper portion 54' and the inner edge of central opening 38'. Helical spring 52' biases valving member 44' of assembly 17' toward a normal dispensing configuration in the manner previously described with reference to assembly 17. Thus, if the valve of container 10' is opened, typically by pressing downwardly on the top 37' of cap 36', material will flow from container 10' to port 25' along the path defined by passages 22' and 24'.

For refilling container 10 from container 10', cover 60 of container 10 is opened and actuator assemblies 17, 17' are pushed coaxially together into the position shown in FIG. 4. This movement first seats portion 54' within recess 56, and then pushes the valve members 44, 44' of each assembly toward the respective valve stem 16, 16', flexing the assembly's sealing gasket 40, 40' downwardly over the inlet ends of the dispensing conduits 24, 24' and sealing the conduits 24, 24' from transfer passages 22, 22'. As springs 52 and 52' are of substantially less actuating force than the springs within the valves of container 10 and 10' holding stems 16 and 16' movement of valving members 44 and 44' is completed prior to movement of stems 16 and 16'. The downward movement of the valving members also forces the respective transition portions 46, 46' partially through the respective gasket openings 42, 42', so that ports 59, 59' are open and provide communication 35 between the respective refilling passages 58, 58' and passages 22, 22'. As the actuator assemblies are pressed further together, the respective valve stems 16, 16' of the devices will be moved axially, opening their 40 valves and permitting flow of material from the refilling container 10' to dispenser 10 along the path defined by passage 22', refill passage 58', refill passage 58 and passage 22.

When, after refilling, the assemblies are separated, 45 and after the valves of containers 10 and 10' close, springs 52, 52' push the respective valving members 44, 44' back into their dispensing configuration, in which flanges 50, 50' engage caps 36, 36', and gasket 40, 40' and tips 48, 48' seal refilling passages 58, 58' from passages 22, 22'. Cap 60 is then reclosed and the refilled daughter package may be used in conventional manner.

Other embodiments within the scope of the following claims will occur to those skilled in the art.

What is claimed is:

1. In a pressurized dispensing package including a container for storing a material to be dispensed under pressure, a discharge passage structure and a valve assembly for controlling the discharge of said material from said container through said discharge passage structure, an actuator device mounted on said discharge passage structure, said actuator device including structure defining a dispensing passage having an inlet port at one end and a dispensing port at the other end and a transfer passage providing communication between said discharge passage structure and said inlet port of said dispensing passage,

a resilient sealing member mounted adjacent said inlet port; and
 a valving member mounted in engagement with said sealing member for movement relative to said transfer passage defining structure,
 said valving member defining a refilling conduit extending through said valving member to a port at an exterior surface of said valving member,
 said sealing member being movable in response to movement of said valving member between a first position in which said sealing member seals said refilling conduit from said transfer passage and a second position in which said sealing member seals the inlet port of said dispensing passage and said refilling conduit is in communication with said transfer passage.

2. The device of claim 1 including means biasing the assembly toward said first position.

3. The device of claim 1 wherein the valving member is circular in transverse cross-section and the refilling conduit extends generally axially of the valving member from an axially-facing surface thereof and thence angularly to an exterior surface thereof.

4. The device of claim 3 wherein the valving member includes a frusto-conical transition portion adjacent the end thereof spaced from the axially-facing surface.

5. The device of claim 4 wherein the refilling conduit terminates in a port at the surface of the transition portion.

6. The device of claim 4 wherein said valving member includes an annular flange spaced from the transition portion and including spring means engaging the flange for biasing the assembly towards said first position.

7. The device of claim 4 wherein the valving member includes a projecting top on the side of the transition portion opposite the axially-facing surface and the refilling conduit terminates in a port at the surface of one of the transition portion and the tip.

8. The device of claim 1 wherein the sealing member includes an opening extending therethrough, the valving member extending within and sealingly engaging the periphery of the opening in said first position.

9. The device of claim 8 wherein the sealing member is substantially planar in its unflexed configuration and is supported at an area spaced from the opening therethrough.

10. The device of claim 9 wherein the sealing member defines a portion of said transfer passage.

11. The device of claim 8 wherein the valving member includes a frusto-conical transition portion adjacent the end thereof spaced from the axially-facing surface, the refilling conduit terminates in a port at the surface of the transition portion, and the sealing member engages the valving member intermediate the refilling conduit port and an axially-facing surface thereof in said first position and engages the valving member on the side of the refilling conduit port opposite the axially-facing surface in said second position.

12. The device of claim 11 wherein the transfer passage includes a frusto-conical wall portion, the inlet port of said dispensing passage is disposed in said frusto-conical wall portion, and the sealing member overlies said inlet port at the wall portion in said second position.

13. The device of claim 11 wherein said assembly defines an internal chamber in which at least a portion of the valving member is mounted and having an opening extending through a wall of the chamber to the exterior of the assembly, and the valving member includes a radially-projecting flange intermediate the length thereof, the portion of the valving member on the side of the flange opposite the transition portion extending to within the wall opening.

14. The device of claim 13 including spring means engaging one surface of the flange for biasing the assembly toward its first position and wherein another surface of the flange engages said chamber wall in said first position.

15. The device of claim 13 wherein the portion of the valving member on the side of the flange opposite the transition portion includes an axially-facing end surface and a cavity extending within the member from the end surface.

16. The device of claim 13 wherein the assembly includes a cover hingedly movable between a position overlying the cavity opening and a position spaced from the cavity opening.

17. A system for refilling one pressurized dispensing package from another comprising, in combination:

the pressurized dispensing package as claimed in claim 1; and

30 a second pressurized dispensing package having a material dispensing structure adapted for mating engagement with said valving member of the actuator device of said first package,
 said packages being arranged so that relative movement of said two packages towards one another with the material dispensing structure of said second package in mating engagement with the valving member of the actuator device of said first package actuates the valves of said two packages to permit flow of material from one of the packages into the other.

18. The system of claim 17 wherein the second package includes an actuator assembly, a transfer passage, a dispensing passage having an inlet port at one end and a dispensing port at the other end, a resilient sealing member mounted adjacent said inlet port, and a valving member mounted in engagement with said sealing member for movement relative to said transfer passage and defining a refilling conduit interior thereto, a portion of which extends angularly of the direction of movement of the valving member to a port at an exterior surface of the valving member, said sealing member being movable in response to movement of said valving member between a first configuration in which said sealing member seals said refilling conduit from said transfer passage and a second configuration in which said sealing member seals said dispensing passage from said transfer passage and said refilling conduit is in communication with said transfer passage.

19. The system of claim 18 wherein the valving member of one of said packages includes a recess for receiving a portion of the valving member of the other of said packages, the refilling conduits of the respective valving members being in communication when said portion of the valving member of said other package is seated within said recess of the valving member of said one package.

20. The system of claim 19 wherein the assembly of each of said packages includes an internal chamber in which at least a portion of the valving member of the respective assembly is mounted and an opening extending through a wall of the chamber to the exterior of the respective assembly, each of the valving members includes a radially-projecting flange intermediate the length thereof and a portion on the side of the flange thereof opposite the sealing member of the respective assembly projecting into the opening, the height of one of the projecting portion of the valving member of one of the assemblies being greater than the thickness of

the wall of the one assembly and the height of the projecting portion of the valving member of the other of the assemblies being not greater than the thickness of the wall of the other assembly.

5 21. The system of claim 20 wherein one of the projecting portions is of greater diameter than the other of the projecting portions, the openings of both assemblies are of diameter substantially equal to that of the greater diameter projecting portion, and the recess is of 10 diameter substantially equal to that of the lesser diameter projecting portion.
